UNITED STATES PATENT OFFICE.

SIDNEY G. SPENCER, OF SHREVEPORT, LOUISIANA.

TAG-FASTENER.

SPECIFICATION forming part of Letters Patent No. 694,801, dated March 4, 1902.

Application filed July 6, 1901. Serial No. 67,258. (No model.)

To all whom it may concern:

Be it known that I, SIDNEY G. SPENCER, a citizen of the United States, and a resident of Shreveport, in the parish of Caddo, in the 5 State of Louisiana, have made certain new and useful Improvements in Tag-Fasteners, of which the following is a specification.

My invention is an improvement in tag-fasteners, and has for an object to provide a 10 novel construction of fastener for application to the bolt-board of bolts of cloth or other fabric, the invention seeking to provide a fastener whose end arms will conform to and rest snugly against the ends of the boards, 15 while the side arms will rest snugly against the sides of the boards, and the prongs or hooks will bite into the opposite faces of the board, the fastener being readily applied to and removed from the board; and the invention 20 consists in the novel construction of the tag-fastener, as will be hereinafter described and claimed.

In the drawings, Figure 1 shows the fastener applied to a bolt of cloth. Fig. 2 is a 25 side view, and Fig. 3 a top plan view, of the clasp removed from the board, and Fig. 4 is an end elevation of the fastener looking at the coiled end thereof; and Figs. 5 and 6 are end views, broken away, of bolt-boards of different thicknesses with the fastener applied.

In the construction shown the tag-fastener is formed, preferably, of suitable spring-wire cut a suitable length and formed at its middle with a coil A, from the opposite ends of 35 which project the end arms B, which extend in reverse directions from the opposite ends of the coil and are made of sufficient length to extend in use to the opposite faces of the bolt-board 1 on which the goods are rolled. 40 The side arms C extend on straight lines from the outer extremities of the end arms B at approximately right angles thereto and incline toward their free ends toward each other both longitudinally and laterally, so their extremities are approximately opposite or adjacent to each other, as will be understood from Fig. 3. This inclination of the side arms longitudinally toward each other is shown in the side view, Fig. 2, while the inclination of the said side arms laterally toward each other is illustrated in the top plan view, Fig. 3. The longitudinal inclination shown in Fig. 2 is to give the desired tension on the prongs or hooks D at the ends of the 55 arms C to cause them to bind in the bolt-board,

while the lateral inclination so adjusts the said hooked ends as to cause them to engage upon the faces of the bolt-board at opposite points. The arrangement of the clamping-arms to project from the opposite ends of the 60 coil is such as to give the fastener a twisting tension, so it will twist if applied to a board of less thickness than the distance between the ends of the arms B and cause the side arms C to lie flat against the bolt-board, as 65 will be understood from the end views 5 and 6, in the former of which the fastener is shown applied to a bolt-board of a thickness equal to the distance between the ends of the arms B, while in Fig. 6 the bolt-board is much 70 thinner and the fastener is shown twisted by its tension so the side arms C will rest flat against the thinner bolt-board. It will be understood from this that whether the bolt-board be thick, as shown in Fig. 5, or thinner, as shown in Fig. 6, the side arms C will 75 lie close against the bolt-board, and thus avoid any projection which would operate to cause the goods to present a bad appearance, as goods wrapped on a bolt-board with end 80 projections would not appear in a merchantable manner on the shelf. By my invention the goods can be rolled smoothly and evenly and will present a good appearance at all times.

Having thus described my invention, what I claim as new, and desire to secure by Letters Patent, is—

The tag-fastener herein described, composed of wire having a central coil, end arms projecting outwardly in reverse directions from the opposite ends of the coil, the side arms extending from the outer extremities of the end arms at approximately right angles thereto and inclining inwardly toward their extremities, both longitudinally and laterally, and provided at such extremities with inwardly-projecting hooks all substantially as described, whereby the longitudinal and lateral inclination of the side arms will cooperate with the central coil in causing the fastener to adjust to the thickness of the bolt-board, and the hooked ends to engage upon the faces of the bolt-board, all substantially as and for the purposes set forth.

SIDNEY G. SPENCER.
